DESIGN FOR A NECKLACE OR THE LIKE

Louis C. Mark, Providence, R. I., assignor to Rice-
Weiner and Company, Providence, R. I.

Application August 2, 1941, Serial No. 102,668

Term of patent 3½ years

To all whom it may concern:

Be it known that I, Louis C. Mark, a citizen of the United States, residing in the city of Providence, county of Providence, State of Rhode Island, have invented a new, original, and ornamental Design for a Necklace or the like, of which the following is a specification, reference being had to the accompanying drawing, forming part thereof.

Fig. 1 is a front elevational view of a necklace or the like embodying my new design, and

Fig. 2 is an edge elevational view of the pendant of said necklace, the supporting chain being removed.

I claim:

The ornamental design for a necklace or the like, substantially as shown.

LOUIS C. MARK.
